UNITED STATES PATENT OFFICE

JAMES H. DAVISON, OF CHICAGO, ILLINOIS, ASSIGNOR TO WILSON-JONES COMPANY, OF CHICAGO, ILLINOIS, A CORPORATION OF MASSACHUSETTS

CHAIN POST BINDER

Application filed March 31, 1930. Serial No. 440,202.

This invention relates to a chain post binder and concerns itself primarily with terminal heads for the ends of the chain that bear directly upon the loose sheets and provide a better compression and that extend into one of the clamping members which is provided with means for locking said terminal heads thereto.

The invention comprises the novel structure and combination of parts hereinafter described and more particularly pointed out and defined in the appended claims.

In the accompanying drawing which illustrates a preferred form of this invention and in which similar reference numerals refer to similar features in the different views:

Figure 1 is a perspective view of a chain post binder involving this invention.

Figure 2 is an enlarged transverse sectional view through the binder taken through the two clamping members upon the line II-II of Figure 1 looking in the direction of the arrows.

Figure 3 is an enlarged fragmentary sectional view taken upon the line III-III of Figure 2 with the slide omitted.

Figure 4 is an elevational view of one of the terminal heads for the chain post.

The illustrated binder consists of a pair of cover members 1 which respectively carry the clamping members 2 and 3. A screw rod 4 having right and left hand threads is secured in the clamping member 3 for rotation and this screw rod carries a pair of nuts 5 to which the chain posts 6 are attached as is well known in the art. Each chain post carries a terminal head 7 which is provided with a flange 8 adapted to engage the loose sheets 9 and compress the same as shown in Figure 2.

Above the flange 8, each terminal head is provided with a groove 10 adapted for receiving a tubular slide latch 11 as will later more fully appear. These heads 7 are provided with threaded portions 12 which are adapted for being screwed into suitable threaded sockets in the end plates 13 of the chain so that the same may be removed and extension-post sections added. The upper clamping members 2 is provided with suitable apertures through which the upper portions of the terminal

heads 7 extend as shown more clearly in Figures 2 and 3. The flange 8 on each screw however is larger than said aperture and cannot pass therethrough and is forced to bear against the top of the loose sheets and impart a compression thereto.

The aforementioned latching slide 11 is mounted in the upper clamping member and is provided with an arcuate notch at one end for engaging the groove 10 in one terminal head. This tubular slide 11 is also provided with a slot 11a for receiving the other post, and one end of this slot 11a is designed for engaging the groove of the adjacent post.

The tubular slide is adapted to be actuated from one side of the binder and to this end, the unnotched terminal of the tubular slide is provided with an upstanding lug 14 in which a screw 15 is rotatably anchored. The screw 15 is threaded in one of the end plugs 16 that close the ends of the clamping member and is provided with a polygonal terminal 17 for receiving a key whereby the same may be rotated.

In its assembled relation, the clamping members are held together by the chain post and the slide 11 which engages the grooves 10 in the terminal heads of the chain posts. When it is desired to lengthen the chain, the terminal heads may be unscrewed and sectional posts may be added in order to increase the capacity of the binder. In order to do this, the latching slide 11 must first be actuated to release the terminal heads 7 from engagement therewith whereupon the upper clamping member 2 may be disengaged from the heads 7.

It will be noted that the terminal heads 7 are concealed in the upper binder head 2 which does not apply any pressure to the loose sheets which are held in compressed relation by the pressure of the flanges 8 thereon.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. In a chain post binder, a hollow clamping member, take-up mechanism in said clamping member, chain posts connected to said take-up mechanism, terminal heads on said chain posts having flanges for compressing the loose sheets, a second hollow clamping member having apertures for receiving said heads, said heads having grooves and a slide mounted in said second clamping member for engaging said grooves for locking said terminal heads to said second clamping member.
2. In a chain post binder, a pair of hollow opposed clamping members, chain posts connecting said clamping members, a terminal head on each chain post having an enlarged flange adapted for bearing upon said sheets, and said heads extending into one clamping member and means in said clamping member for locking said heads thereto.
3. In a chain post binder, a pair of clamping members, flexible posts connecting said clamping members, said posts having flanged heads adapted for bearing upon the loose sheets and means for locking said heads in the adjacent clamping member.

In testimony whereof I have hereunto subscribed my name at Chicago, Cook County, Illinois.

JAMES H. DAVISON.
